UNITED STATES PATENT OFFICE.

JOHN F. HEMENWAY, OF NEW YORK, N. Y.

PRESSURE-ROLL RELEASE FOR CLOTHES-WRINGERS.

1,220,114.

Specification of Letters Patent. Patented Mar. 20, 1917.

Application filed September 9, 1916. Serial No. 119,176.

To all whom it may concern:

Be it known that I, JOHN F. HEMENWAY, a citizen of the United States, residing at New York city, in the county of New York 5 and State of New York, have invented certain new and useful Improvements in Pressure-Roll Releases for Clothes-Wringers, of which the following is a specification, reference being had therein to the accompanying 10 drawing.

This invention relates to pressure roll release for clothes wringers, the object being to provide a release which is exceedingly simple and cheap in construction, and one 15 which can be readily applied to the ordinary construction of clothes wringer now in use.

Another object of my invention is to provide a pressure release which is operated by 20 a centrally disposed member carried by the top bar so that when the same is depressed, the retaining members will be released in order to release the pressure on the pressure rolls so that in case of an accident or foreign object becoming caught between the 25 rolls the pressure can be instantaneously released.

Another and further object of the invention is to provide a pressure release which 30 is so constructed that the same can be quickly attached to a clothes wringer and detached therefrom so as to convert an ordinary clothes wringer into a safety wringer with pressure releasing means for the pressure rolls.

Other and further objects and advantages 35 of the invention will be hereinafter set forth and the novel features thereof defined by the appended claims.

40 In the drawings,

Figure 1 is a front elevation partly in section of a clothes wringer showing the application of my improved construction of pressure release thereto; and

45 Fig. 2 is a top plan view of the same.

Like numerals of reference refer to like parts in the several figures of the drawing.

In the drawing I have shown the application 50 of my invention to a clothes wringer of the ordinary construction comprising a frame 1 having slotted side bars in which

are mounted bearings for the shafts 2 and 3 of the pressure rolls 4 and 5 which are provided with the usual meshing gears enclosed by a casing, the upper bearings 3 carrying spring supports 6 on which are arranged pressure springs 7 engaged by bearing plates 8 carried by a pressure bar 9.

Slidably mounted within the slotted upper end portions of the slotted side bars of the wringer frame, is a top bar 10 which is provided with threaded boxes 11 in which are mounted pressure screws 12 which engage the plates 8 of the pressure bar 9 in order to exert the pressure in the pressure 65 spring so that the rolls will be held under tension.

Secured to each of the side bars of the wringer frame is a keeper 13 which is in the form of a block of metal secured to the inner face of the side bar to one side of the slot, and it will be noticed that in placing these keepers in position, one is arranged on one side of the top bar 10 and the other is arranged upon the opposite side. Secured 75 to the top bar 10 adjacent each end is a depending bracket 14 on each of which is mounted a pivoted latch 15 coöperating with the keeper 13 as clearly shown in Fig. 1 in order to hold the top bar 10 in predetermined position so that the pressure screws can exert the pressure on the pressure rolls through the medium of the pressure bar and pressure springs. Each of the pivoted latches 15 is provided with a tail portion 16 80 which is pivotally mounted on a transversely arranged pin 17 carried by the lower end of the shank 18 of a push button 19 which is slidably mounted in a bore 20 formed in the top bar 10 and surrounded by 85 a coil spring 21 as shown in Fig. 1 so that the push button 19 is normally held in the position shown in Fig. 1 in order to hold the pivoted latches 15 under the keepers 13 so that the top bar will be held in its proper 90 position within the wringer frame.

When it is desired to instantaneously release the pressure on the pressure rolls by striking the push button 19, the pivoted latches 15 will be thrown out of contact 100 with the keepers 13 so as to allow the top bar 10 to move vertically within the wringer

frame which will instantaneously release the pressure means so as to allow the upper pressure roll to move vertically.

From the foregoing description it will be seen that in order to apply my improved construction of pressure release to a clothes wringer of the ordinary construction, it is only necessary to bore a hole to form a bearing for the shank of the push button and to 10 secure the keepers and brackets respectively to the top bar and side bars of the wringer frame.

I claim:

1. A clothes wringer comprising a frame 15 having pressure rolls and pressure means for said rolls, a top bar movably mounted within said frame having pressure screws for adjusting said pressure means, keepers secured to the inner faces of the side bars 20 of said frame, pivoted latches carried by the top bar engaging said keepers for holding the top bar in predetermined position, and a slidably mounted member carried by the top bar having a pivotal connection with 25 the inner ends of said pivoted latches for moving said pivoted latches out of contact with said keepers to release said top bar.

2. A clothes wringer, comprising a frame having pressure rolls and pressure means for 30 said rolls, a top bar movably mounted within said frame having pressure screws for adjusting said pressure means, keepers carried by the side bars of said frame, pivoted latches carried by said top bar engaging 35 said keepers, and a push button slidably mounted within the top bar having a connection with said latches for moving said latches out of contact with said keepers to release said top bar.

40 3. A clothes wringer, comprising a frame having pressure rolls and pressure means for said rolls mounted therein, a movably mounted top bar carrying means for adjusting said pressure means, keepers carried 45 by the side bars of said frame, brackets carried by the top bar of said frame, pivoted latches mounted on said brackets engaging said keepers, and a spring actuated push button mounted in said top bar having a 50 connection with said latches.

4. A clothes wringer, comprising a frame having pressure rolls and pressure means for 55 said rolls mounted therein, a top bar movably mounted within said frame having means for adjusting said pressure means, keepers carried by the side bars of said frame, a depending bracket secured to said top bar adjacent each end, a pivoted latch on each of said brackets engaging said keepers, a push button having a shank slidably mounted within said top bar, a cross bar carried by the shank of said push button having a connection with said latches, and

a spring surrounding the shank of said push button above said top bar for normally holding said latches in engagement with 65 said keepers.

5. A clothes wringer, comprising a frame having pressure rolls and pressure means for said rolls mounted therein, a top bar 70 movably mounted within the frame of said wringer having pressure screws for adjusting said pressure means, keepers carried by the side bars of said frame, brackets carried by the movable top bar, a pivoted latch 75 mounted on each of said brackets and adapted to engage one of the keepers, a push button having a shank slidably mounted within said top bar, a cross bar carried by the lower end of said push button having a connection with said latches, and a spring for 80 normally holding said push button in raised position.

6. A clothes wringer, comprising a frame having pressure rolls and pressure means 85 for said rolls mounted therein, a top bar movably mounted in said frame having pressure screws for adjusting said pressure means, said top bar being provided with a centrally disposed vertical bore, a push 90 button having a shank slidably mounted within said bore, a spring surrounding said push button above said top bar, the shank of said push button being provided with lateral projections at the lower end thereof, 95 brackets carried by said top bar, latches mounted upon said brackets having tail portions pivotally mounted upon the lateral projections of said push button, and keepers carried by the side bars of said pressure 100 rolls adapted to be engaged by the latches.

7. A clothes wringer, comprising a frame having pressure rolls and pressure means for said rolls, a top bar movably mounted in 105 said frame having pressure screws for adjusting said pressure means, keepers carried by the side bars of said frame, movable latches carried by the top bar engaging said keepers for holding the top bar in predetermined position, and a movably mounted push button carried by the top bar having a connection with said movable latches for 110 moving said latches out of contact with said keepers to release said top bar.

8. A clothes wringer, comprising a frame 115 having pressure rolls and pressure means for said rolls, a top bar movably mounted in said frame having pressure screws for adjusting said pressure means, keepers carried by the inner faces of the top bars of 120 said frame, depending brackets carried by the top bar, pivoted latches mounted on said brackets engaging said keepers for holding said top bar in predetermined position within said frame, said latches being provided 125 with tail portions having apertured ends, a

spring-actuated push button mounted in said top bar, and a pin carried by the lower end of said push button extending through the apertured ends of the tail portions of 5 said latches for moving said latches out of engagement with said keepers on the depression of said push button.

In testimony whereof I hereunto affix my signature in the presence of two witnesses.

JOHN F. HEMENWAY.
